UNITED STATES PATENT OFFICE.

CHARLES T. JUDD, OF SOMERVILLE, MASSACHUSETTS, ASSIGNOR TO J. DUNCAN COMPANY, OF EVERETT, MASSACHUSETTS, A CORPORATION OF MASSACHUSETTS.

OVERHEAD TRAMWAY-SWITCH.

1,377,134.

Specification of Letters Patent.

Patented May 3, 1921.

Application filed January 13, 1921. Serial No. 436,960.

To all whom it may concern:

Be it known that I, CHARLES T. JUDD, a citizen of the United States, and resident of Somerville, county of Middlesex, State of 5 Massachusetts, have invented an Improvement in Overhead Tramway-Switches, of which the following description, in connection with the accompanying drawing, is a specification, like characters on the drawing 10 representing like parts.

This invention relates to improvements in overhead switches for tramway rail systems such as are ordinarily used in beef houses, cold storage houses and in other places where 15 the load is suspended from a traveler riding along the rail system.

The object of the invention is to provide a switch for use in any type of rail system wherein the traveler is provided with flanged 20 guides such for example as flanged wheels riding on both the top and bottom edges of the rails and generally known as the safety type.

The nature and objects of the invention 25 will appear more fully from the accompanying description and drawings and will be particularly pointed out in the claims.

The invention may be embodied in various forms of switches operated in various ways 30 and acting to connect and disconnect rails arranged in different ways but for convenience of disclosure of a preferred form, it is shown as embodied in a switch of the general type illustrated in the patent to Werner, No. 35 571,607, granted November 17, 1896.

The drawings illustrate a simple and preferred form of switch of the general Werner type with a preferred form of the present invention embodied therein.

40 In the drawings:

Figure 1 is a view in perspective showing a preferred form of switch embodying the invention in position for maintaining a continuous main rail with a portion of the main 45 rail, a portion of a branch rail and a portion of a traveler shown in dotted lines.

Fig. 2 is a view similar to Fig. 1 with the switch shown in position connecting the main and branch rails.

50 Fig. 3 is a view in transverse section of the same construction shown in Fig. 2.

Fig. 4 is a detail in bottom plan view of the portion of the main rail section shown in full lines in Fig. 1.

As the general type of overhead tramway 55 system with which this invention is concerned is well known and familiar to those skilled in the art no description is necessary. Such a system comprises rails usually formed of flat bars of iron arranged vertically and supported from the ceiling by suitable hangers. The load, such for example as a carcass 60 of beef, is suspended from a traveler which rides along the rail. The upper end of such a traveler is shown as comprising a bar 1 having a flanged guide herein shown as a flanged wheel 2 straddling and riding upon the upper edge of the rail. In the type of 65 tramway shown the traveler is also provided with a second flanged guide such for example 70 as the flanged wheel 3 riding on the bottom edge of the rail. The use of the two flanged guides such as the flanged wheels 2 and 3 prevent the traveler with its load from being jarred or thrown off from the rail and is a 75 very desirable type.

It is necessary in such an overhead tramway system to move the traveler with its load from one rail to another and when the flanged guides riding on the top and bottom 80 edges of the rail are employed as in this case it has heretofore been a difficult problem to provide for the passage of the traveler from one rail to another. In this invention such 85 passage of the traveler from one rail to another is secured without releasing the hold of the flanged guide 3 at the bottom edge of the rail from the rail. Thus the safety feature of the system is maintained by this invention.

In describing the invention one rail is 90 herein referred to as the main rail and another rail as the branch rail but these terms are relative merely as either rail may be the main rail and either rail the branch rail. So also the main rail may be either straight or 95 curved and the branch rail either straight or curved as the particular conditions may require. In the illustration of the invention the main rail 4 is for convenience shown as straight and the branch rail 5 is for convenience shown as curved.

The switch comprises a suitable supporting bracket which is secured at the side of the main rail 4 opposite the end of the branch rail 5. This may be effected in any desired 100 manner. In the form illustrated the switch bracket is shown as a separate piece adapted to be bolted to the main rail 4 by bolts pass-

ing through holes 7 and a portion of the main rail 8 is shown as formed integral with the bracket 6 but these are details which may be varied as desired, the only important feature 5 being that the switch bracket is rigged with the main rail at the side of the main rail and opposite the end of the branch rail.

The upper portion 9 of a section of the main rail opposite the end of the branch rail, 10 as shown for example in full lines in Fig. 1, is made separate from the rest of the main rail and is mounted on the bracket 6 to be movable into and out of position to form a continuation of the main rail. In Fig. 1 it 15 is shown in position thus making a continuous main rail.

The section 9 may move into and out of position in any desired manner. It is conveniently shown as sliding on the switch bracket by means of an extension 10 resting 20 on the top of the switch bracket and in this case the sliding movement is shown as a pivotal swinging movement, the section 9 and extension 10 being pivoted to the switch bracket by a vertical pivot 11.

A second rail section 12 is also mounted on the switch bracket to move out of and into position to disconnect and connect the top edges of the main and branch rails. In the 30 particular form illustrated this section 12 is curved and when in position, as shown in Fig. 2, makes the top edge of the front rail 5 connect with the top edge of the main rail 4. This second rail section 12 may also be 35 mounted on the switch bracket and move out of and into position in any desired manner. It is conveniently shown as swinging in a vertical direction its rearward extension being for that purpose pivoted on a horizontal pivot on the upstanding arms 15 of the switch bracket.

The respective movements of the two switch sections may be effected in any desired manner. Preferably the movement of 45 the one is effected by the movement of the other and this in turn preferably by a construction of the type shown in the Werner patent above mentioned. For this purpose the rail section 12 is provided with a stud or 50 spur 16 adapted to enter and engage an aperture 17 in the first rail section. The rail section 12 is also provided with a heel 18 adapted to contact with the lower edge 19 of the extension 10 of the rail section 9.

55 In the form illustrated the rail section 12 is also preferably shown as the one which is operated and which in turn operates the rail section 9. For this purpose the rail section 12 has an upward and rearward inclined arm 60 20 to which an operating rod may be attached in the hole 21. The operation is similar to that shown in the Werner patent above noted. Assuming that the switch is in the position shown in Fig. 1 and it is desired to shift the parts to the position shown

in Fig. 2 the operator pushes up on the arm 20 thus swinging the rail section 12 downwardly. As it falls into the connecting position with the branch rail the stud 16 enters the aperture 17 and withdraws the rail section 9 from connecting position and the parts 70 assume the position shown in Fig. 2. When it is desired to shift the switch from the position shown in Fig. 2 to that shown in Fig. 1 the operator pulls down on the arm 20 thus 75 swinging the rail section 12 out of position. As this movement takes place the stud 16 acting against the front wall of the aperture 17 cams the rail section 9 into position and the final movement is given by the heel 18 80 pressing against the edge 19. The parts then assume the position shown in Fig. 1 wherein it will be noted the weight of the section 12 acts by gravity to hold the section 9 in place. 85

In this invention the lower portion of the main rail section 8 opposite the end of the branch rail 5 is provided with a recess 22 in its bottom edge at the point where the branch rail 5 if prolonged would engage the 90 main rail. The side walls 23 of this recess 22 are preferably beveled as illustrated to extend in the general direction of the line of travel of the flanged guide 3 when passing 95 between the main and branch rail. 95

This recess 22 does not interfere with the passage of the flanged guide 3 along the bottom edge of the main rail and with the beveled arrangements of the side walls shown one of the flanges of the flanged guide 3 100 will substantially always be in contact with the main rail when the guide passes the recess.

The second rail section 12 in this invention is provided with a depending filler section 105 24 of a size and form such that when it is in connecting position as shown in Fig. 2 it will continue the bottom edge of the branch section 5 up to the face of the main rail section 8 adjacent the recess 22. Preferably 110 the inner edge 25 of this filler section 24 is beveled to enable it to fit quite closely against the outer face of the main rail when in connecting position.

It will now be seen that when the rail section 12 is in connecting position as shown in Fig. 2 the flanged guide 3 is permitted to pass between the main and branch rail and is controlled in its passage by the filler section 24 and the recess 22 so that it passes 120 along a practically continuous rail and can not be swung or jarred out of position.

Thus the switch of this invention provides a system in which a main and branch rail may be connected or disconnected as desired and in which a traveler provided with top and bottom flanged guides may pass 125 along either the main rail or branch rail and the main rail at the switching point and maintain a firm grip on the top and bottom 130

edges of the rail thus producing a safety switch in this type of overhead tramway rail system.

Having thus described my invention, what I claim as new and desire to secure by Letters Patent, is:

1. A switch for an overhead tramway rail system traversed by a traveler having flanged guides riding on both the top and bottom edges of the rails comprising a 10 switch bracket adapted to be secured at the side of the main rail opposite the end of a branch rail the upper portion of a section of the main rail opposite the end of the 15 branch rail being mounted on the switch bracket and movable into and out of connecting position in the main rail, the lower portion of said section having a recess to permit the passage of the flange of the bottom 20 guide when passing between the main and branch rail, and a second rail section mounted on the switch bracket and movable out of and into position to disconnect and 25 connect the top edges of the main and branch rails and provided with a depending filler section acting when in connecting position to continue the bottom edge of the branch section up to the face of the main rail adjacent the recess and thus permit and 30 control the passage of the flanges of the bottom guide between the main and branch rails.

2. A switch having the construction defined in claim 1 together with means controlled by the movement of the one rail sec- 35

tion into and out of connecting position for moving the other rail section out of and into connecting position.

3. A switch having the construction defined in claim 1 in which the upper portion 40 of the main rail section is pivotally mounted on the switch bracket to swing vertically into and out of connecting position and in which the second rail section is slidably mounted on the switch bracket to move into 45 and out of connecting position.

4. A switch having the construction defined in claim 1 in which the side walls of the recess are beveled to extend in the general direction of the line of travel of the 50 flanged guide in passing between the main and branch rail.

5. A switch having the construction defined in claim 1 in which the inner edge of the filler section is beveled to enable it to 55 fit against the outer face of the main rail when in connecting position.

6. A switch having the construction defined in claim 1 in which the side walls of the recess are beveled to extend in the general direction of the line of travel of the 60 flanged guide when passing between the main and branch rail and in which the inner edge of the filler section is beveled to enable it to fit against the outer face of the main 65 rail when in connecting position.

In testimony whereof, I have signed my name to this specification.

CHARLES T. JUDD.
